DESIGN FOR A SANDBLAST CASING

Ormonde Bogert, Maplewood, and William B. Hewitt, Orange, N. J., assignors to Leiman Bros., Inc., Newark, N. J., a corporation of New Jersey

Application June 26, 1945, Serial No. 120,344

Term of patent 3½ years

(Cl. D37—1)

To all whom it may concern:

Be it known that we, Ormonde Bogert and William B. Hewitt, citizens of the United States, and residents respectively of Maplewood, in the county of Essex and State of New Jersey, and of Orange, in the county of Essex and State of New Jersey, have invented a new, original, and ornamental Design for a Sandblast Casing, reference being had to the accompanying drawing, forming a part thereof.

Fig. 1 represents a perspective view of a sandblast casing embodying my new design;

Fig. 2 represents a side elevation thereof;
Fig. 3 represents a front elevation thereof; and
Fig. 4 represents a top plan view thereof.
The dominant features of our new design reside in the portions shown in full lines.

I claim:

The ornamental design for a sandblast casing, substantially as shown and described.

ORMONDE BOGERT.
WILLIAM B. HEWITT.
